UNITED STATES PATENT OFFICE.

CHARLES C. GATES, OF DENVER, COLORADO.

DESIGN FOR A RUBBER TIRE.

• 54,408.

Specification for Design.

Patented Feb. 10, 1920.

Application filed August 29, 1919. Serial No. 320,735. Term of patent 3½ years.

To all whom it may concern:

Be it known that I, CHARLES C. GATES, a citizen of the United States, residing at the city and county of Denver and State of Colorado, have invented a new and original ornamental Design for Rubber Tires, of which the following is a specification, reference being had to the accompanying drawing, forming a part thereof.

In this drawing, Figure 1 is a fragmentary sectional view, and Fig. 2 a fragmentary plan view, of a rubber tire, showing my new design.

I claim:

The ornamental design for a rubber tire as shown.

In testimony whereof I affix my signature.
CHARLES C. GATES.
